CLAIM

The ornamental design for a hand tool, as shown and described.

DESCRIPTION

FIG. 1 is a perspective view of a hand tool showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is an additional perspective view from an opposite end of the FIG. 1 view;

FIG. 9 is an enlarged view of the portion indicated in FIG. 1;

FIG. 10 is an enlarged view of the portion indicated in FIG. 2;

FIG. 11 is an enlarged view of the portion indicated in FIG. 3;

FIG. 12 is an enlarged view of the portion indicated in FIG. 6;

FIG. 13 is an enlarged view of the portion indicated in FIG. 7; and,

FIG. 14 is an enlarged view of the portion indicated in FIG. 8.

The broken lines depict portions of the hand tool in which the design is embodied that are not considered part of the claimed design.
